UNITED STATES PATENT OFFICE.

MARY IRENE SNAPE, OF SPRINGFIELD, ILLINOIS.

ENVELOPE.

Original application filed January 7, 1922, Serial No. 527,575. Divided and this application filed July 29, 1925. Serial No. 46,800.

To all whom it may concern:

Be it known that I, MARY IRENE SNAPE, a citizen of the United States, residing at Springfield, in the county of Sangamon and State of Illinois, have invented certain new and useful Improvements in Envelopes, of which the following is a specification.

This invention has reference to envelopes used for mailing purposes in which, things which are ordinarily subject to different postal rates, and which are usually sent in separate envelopes and cartons may be inclosed in practically one and the same package and the sender thus assured that such things will arrive at their destination together, and is a division of an application filed January 7, 1922, Serial No. 527,575.

The invention has for its principal object to provide a package for mailing purposes in which may be inclosed automobile license number plates issued by the automobile department of the several States, and also the registration card issued by such departments. These two things, the license plate and registration card, are each subject to different postal rates, one being first class, and the other usually fourth class. To the accomplishment of this end, the package is formed with two compartments or pockets; one a large compartment or pocket to contain the license plates and designed to be accessibly fastened, and the other a relatively smaller compartment or pocket to contain the registration card and designed to be inaccessibly sealed. The latter compartment or pocket is preferably provided with a window in one of its walls to expose the name and address of the addressee to whom the plates and the card are being mailed.

A further object of the invention is to form the envelope from a blank made from a single sheet of material, paper or cardboard, and to so design and cut the blank that the small compartment or pocket for the registration card may be located at one end of the package with an opening thereinto at the end of the package, for the insertion of the registration or address card therein.

The invention contemplates a two compartment envelope for the purposes herein stated, and for all and such other purposes

in which it may be desirable to mail things subject to different postal rates.

That the invention may be more fully understood, reference is had to the accompanying drawings forming a part of the present description, illustrating a preferred embodiment of the invention, in which:

Figure 1 is a front view of an envelope embodying my invention, the smaller compartment or pocket preferably having an opening therein at the end of the envelope, and the front wall broken away to show a certain construction;

Figure 2 is a cross-section as the same would appear, if taken on the line 2—2 Figure 1;

Figure 3 is an enlarged sectional view as the same would appear, if taken on the line 3—3 Figure 1;

Figure 4 is a plan view of the blank, when cut, and before the envelope is formed as in Figure 1.

Like characters of reference denote corresponding parts throughout the figures.

Referring to Figures 1 to 4, both inclusive, it will be observed, particularly viewing Figure 4, that the package is made from a single sheet of material which is cut or stamped, so that when scored it may be folded into an envelope constructed, as shown in Figure 1. Such sheet has a front wall 1 and a back wall 2, the line of division between the two being preferably scored, as at *a*, so that 1 and 2 may be folded on each other, as in Figure 1, to provide a large compartment or pocket 10 therebetween. The back 2 along its longitudinal edge is provided with a flap 3 and the line of division between the flap and back is preferably scored, as at *b*, so that when 1 and 2 are folded on each other, the flap 3 is folded over the front wall 1 and pasted down, as shown in Figures 1 and 3. Said back 2, along a part of one transverse edge is provided with a flap 4 and the line of division between said flap and the back is preferably scored, as at *c*, and such flap serves as a closure for inaccessibly sealing the small compartment or pocket, by being folded over the end of the front wall and pasted down, as shown in Figures 1 and 2. The front wall 1, along a part of one transverse edge is provided with a flap 5 and the line of division

between said flap and the front is preferably scored, as at *d*, and such flap is folded over the back 2, after 1 and 2 have been folded on each other, and said flap pasted down 5 against the back, as shown in dotted lines in Figure 1. The front wall 1 has formed integrally therewith the preferably rectangular section 6 joined thereto at one end of the blank and extending a suitable distance the 10 length thereof, the line of division between the front 1 and said section 6 is preferably scored as at *e* that the section 6 may be folded on such scored line and disposed in and between the front and back walls 1 and 2, 15 as very clearly seen in Figures 2 and 3 and in dotted and partly in full lines in Figure 1. Tapes or adhesive strips, A and B are applied to the inner transverse and longitudinal edges of the said section 6 and to the 20 front wall 1 to provide a small compartment or pocket 11 within the compartment or pocket 10 of the envelope. The compartment or pocket 10 preferably opens out of one end of the envelope, whereas the compartment or pocket 11 opens out of the opposite 25 end of said envelope. The compartment or pocket 11 is inaccessibly closed by the flap 4, as previously explained, which is pasted down and over the open end of the compartment or pocket 11 and against the front 30 wall 1, see Figure 1. To guide and insure the entrance of a registration or address card into the compartment or pocket 11 when inserted therein, the section 6 of the 35 front wall 1 at the end of the envelope is provided with a flap 7 and the line of division between said flap and said section is scored, as at *f*, so that when the section 6 is folded in, the flap is also folded in and preferably pasted down against the back wall 2, 40 see Figure 2, and dotted lines Figure 1. The compartment or pocket 10 is preferably accessibly closed by a flap 9 provided on the transverse edge of the front wall 1, opposite 45 the location of flap 5 and the entrance into the compartment or pocket 11. The line of division between said flap 9 and said front wall 1 is scored, as at *g*, that the flap may be folded over the opening leading into compartment or pocket 10 and the said flap secured by any form of metal fastener or by a string and button fastener shown in dotted lines, in Figure 1. That the name and address on the registration or address card 50 55 60 65 70 75 80 85 90 95 100 105 110 115 120 125 130 135

While the foregoing described package has its value as a container for automobile license plates and the registration card, it is 85 of course understood, there is no limit to the

uses to which the same may be put, and whatever the character or description of the thing mailed in the compartment or pocket 10, the compartment or pocket 11 may contain the name and address of the addressee 70 which may appear on a letter, small envelope containing a letter, or other piece of first class mailable matter.

Use of the within described invention obviates the necessity of mailing things, subject to different postal rates, in separate packages, and thereby removes the annoyance due to the delivery of one class of mail with one delivery, and the delivery of a different class of mail matter with another delivery providing of course one or the other pieces of mail is not lost. This has been particularly annoying in the sending of automobile license plates and registration cards. Owners of several cars have been inconvenienced by the receipt of automobile license plates for their different cars, without their registration designating cards, and the plates could not be used until knowledge of which car a particular plate was to be applied thereto. With the package shown and described, however, the plates and card, will arrive together and will be handed to the addressee in practically one and the same 95 envelope, but in a manner that complies with the postal laws, one being sealed and the other unsealed, and each having its own proper postage. The first class postage is applied at C on the front wall 1 of the envelope, while the proper postage for the contents of compartment or pocket 10 is applied at D on the front wall 1.

If the window 12 is omitted, the address can be placed on the envelope, preferably in the area described by the lines *h* and *i* and the right angle edges at one end of the envelope. The return card of the sender may appear at the upper left hand corner of the envelope, in the usual manner.

What I claim is:—

1. In an article of the type set forth, a sheet folded to have a back and a front, the front having a window, an extension on the front at one end thereof folded to underlie the window and to form a smaller compartment, in conjunction with the front, said extension having an outer end in approximate register with the adjacent end of the front to form an inlet for said smaller compartment, a flap on said end of the front between the window and the rear side edge of the front and secured to the back, a flap on the adjacent end of the back secured to the front and over the said outer end of the extension and a flap on the outer end of the extension secured to the back and forming a guide at the inlet of the smaller compartment.

2. A blank for forming a compartment envelope having a large compartment and a

- comparatively smaller compartment for mailing things subject to different postal rates, comprising a sheet of material scored longitudinally to provide front and back 5 portions for the envelope; the front portion provided with a comparatively short extension on its longitudinal edge at one end of the envelope with a scoring between said section and said front portion and also provided 10 with an address window arranged to lie above said section when the same is folded in to lie between said front and back portions, and further provided with flaps at either end thereof with scoring between the 15 same and said front portion, the flap at the end of the said front portion opposite the end having said extension arranged for accessibly closing one end of the large compartment; said extension on the front portion 20 being scored transversely to provide a flap arranged together with the flap on the corresponding end of the front portion to seal that end of the large compartment when said extension is folded in, and the back 25 portion provided with a flap along its longitudinal edge with a scoring between said flap and said back portion for securing the open longitudinal edge of front and back portions when the envelope is folded, and 30 also provided with a flap along one transverse edge arranged to non-accessibly seal the smaller compartment when the envelope is folded.
3. A blank for forming an envelope having compartments differing in size, comprising a single sheet of material scored longitudinally to provide front and back portions for the envelope and one of said compartments and one wall only for the other 35 compartment; the front portion provided with a comparatively short section on its longitudinal edge at one end of the envelope with a scoring between said section and said front portion for the inturning of said section to provide the back wall for said last mentioned compartment, and also provided 40 with an address window arranged to lie above said section when the same is inturned to lie between said front and back portions, and further provided with a flap at each end thereof with a scoring therebetween and said front portion, one flap arranged for accessibly closing one end of the envelope, the other flap arranged for 45 non-accessibly sealing a portion of the other end of the envelope; said section provided with a projection and with a scoring therebetween, which is adapted to secure the section to the back portion of the envelope 50 to provide an opening on the end of the envelope into one of said compartments, the back portion provided with transversely and longitudinally arranged flaps with a scoring 55 between the same and back portion arranged to non-accessibly seal the longitudinal edge of the envelope having said section and for non-accessibly sealing one of said compartments.
4. A blank for forming a two compartment envelope, one relatively larger than the other, comprising a single sheet of material scored longitudinally to provide a front and back for the envelope; the front portion having a flap at one end with a scoring there-between, said flap arranged 70 for accessibly closing one end of the envelope, and provided with a wall-forming section for the smaller of the two compartments at the other end of the envelope with a scoring between said section and said front portion, said front portion and said section each having flaps with scorings between said portion and section and arranged to coact in non-accessibly sealing the end of one compartment, and the back portion having transversely and longitudinally arranged flaps with scoring between the same and the back portion, one of which is arranged to non-accessibly close one longitudinal edge 75 of the envelope and the other arranged to non-accessibly close the open end of the envelope providing communication with the small compartment of the envelope.
5. In an article of the type set forth, a sheet folded to have a back and a front, the front having a window, an extension on the front at one end thereof folded to underlie the window and to form a smaller compartment, in conjunction with the front, said extension having an outer end in approximate register with the adjacent end of the front to form an inlet for said smaller compartment, a flap on said end of the front between the window and the rear side 80 edge of the front and secured to the back 85 and a flap on the adjacent end of the back secured to the front and over the said outer end of the extension.
6. A blank for forming an envelope having a large and a smaller compartment including a sheet foldable to provide a front and a back, an extension on the front at one end thereof having an outer end substantially registering with the adjacent end of the front, said front having a window and said 90 extension being foldable to underlie the window and to form a smaller compartment in conjunction with the front, a flap on the adjacent end of the front between the window and the rear side of the front formed 95 to be secured to the back, a flap on the back adjacent the rear side thereof formed to extend over the said outer end of the extension, and a foldable flap on the outer end of the extension formed for securement to the back to form a guide for the inlet 100 of the smaller compartment.
7. A blank for forming an envelope having a large and a smaller compartment including a sheet foldable to provide a front 105

and a back, an extension on the front at one end thereof having an outer end substantially registering with the adjacent end of the front, said front having a window and said extension being foldable to underlie the window and to form a smaller compartment in conjunction with the front, a flap on the adjacent end of the front between

the window and the rear side of the front formed to be secured to the back, and a flap on the back adjacent the rear side thereof formed to extend over the said outer end of the extension.

In testimony whereof I affix my signature.

MARY IRENE SNAPE.
